UNITED STATES PATENT OFFICE.

WILLIAM H. DOBLE, OF QUINCY, MASSACHUSETTS, ASSIGNOR TO PNEUMATIC SCALE CORPORATION, LIMITED, OF QUINCY, MASSACHUSETTS, A CORPORATION OF MAINE.

CARTON-MARKING ATTACHMENT FOR PACKAGING-MACHINES.

No. 927,225.

Specification of Letters Patent.

Patented July 8, 1909.

Application filed April 5, 1906. Serial No. 310,024.

To all whom it may concern:

Be it known that I, WILLIAM H. DOBLE, citizen of the United States, residing at Quincy, in the county of Norfolk and Commonwealth of Massachusetts, have invented a certain new and useful Improvement in Carton-Marking Attachments for Packaging-Machines, of which the following is a specification, reference being had therein to the accompanying drawings.

In the putting up of goods in packages, and especially of food products, it is quite desirable to have the packages marked with the date on which the goods are put up so that the purchaser can tell whether he is purchasing goods which have been recently put up or not. Sometimes unscrupulous tradesmen represent that the goods have been recently canned or boxed when as a matter of fact they have been put up for a long time, and when the goods prove to be of inferior quality owing to their staleness, the purchaser, not knowing the cause for it, will sometimes blame the parties who pack the goods, thinking that it is through some fault of theirs in the packing or through some defect in the quality of the goods themselves instead of attributing the fault to the tradesman who has unfairly sold to him stale goods, and it is for the protection of the man who puts up the goods that his packages should be marked in some way to indicate when they were put up. It is desirable also that the dealer should know for his own information just when the goods were put up, as it is impossible for him to tell in all cases just how long he has had them in stock. Sometimes also it is desirable to stamp the packages as they are put up with some other designating mark.

The packaging of certain classes of goods which are sold by the package is very largely done by machinery and also is to a large extent automatic.

I have invented a number of machines for both weighing and filling packages automatically, the general type of which is shown and described in Patent No. 714,875, dated December 2, 1902 and Patent No. 716,007, dated December 16, 1902. Those are both for weighing and filling. Sometimes, however, the packages are filled without being weighed. In Patent No. 785,411 dated March 21, 1905 I have shown and described

a machine for closing and sealing the ends of 55 cartons after being filled. My present invention is applicable to such a machine also.

One object of the present invention is to provide an attachment for the package filling machine or sealing machine which is automatically operated to stamp the packages with the date or any other designating mark 60 desired.

For the purpose of illustrating and describing the invention, I have shown in the 65 drawings the device as attached to a weighing and filling machine of the type shown in said Patents No. 714,875 and No. 716,007.

Another object of the invention is to provide means whereby the marking device may 70 be combined with a weighing and filling machine in such manner that the tipping of the scale may actuate or control the marking mechanism.

As the details of the operation of the 75 weighing and filling mechanism do not form a part of the present invention, only so much of the weighing and filling machine is shown as is deemed necessary to properly illustrate the present invention.

The invention will be fully understood from the following description taken in connection with the accompanying drawings, and the novel features are pointed out and clearly defined in the claims at the close of 80 85 the specification.

In the drawings.—Figure 1 is a plan of a portion of a weighing and filling machine with an attachment embodying my invention. Fig. 2 is a side elevation, partly in section, on an enlarged scale, showing a portion of the package moving mechanism with the marking attachment. Fig. 3 is a detail plan on an enlarged scale showing the package in engagement with the lever which operates 90 the marker so that further movement of the package will actuate the marker. Fig. 4 is a detail plan similar to Fig. 3 after the package has moved far enough to bring the marker 95 into engagement with the carton. Fig. 5 is a detail view of the marking disk. Fig. 6 is a detail of a portion of the machine showing a modified form of mechanism for actuating the marking disk in which the lever which carries the marking mechanism is engaged 100 directly by a projection from the carton moving ring instead of by the package itself. 105

Referring now to the drawings:

sents a rotary ring package carrier which rotates in a horizontal plane and is provided with a plurality of outwardly projecting package moving fingers 2.

5 3 represents a table on which the empty cartons or other receptacles 4 are placed. As the ring 1 rotates, one of the cartons 4 is engaged by one of the fingers 2 and pushed along on the track 5 to a position beneath the 10 hopper 6 through which the goods are fed into the carton. Means are provided to cause the ring 1 to rotate intermittently, the ring remaining stationary while the carton is being filled, the means for causing the intermittent motion not being shown in detail as it forms no part of the present invention and is well known.

In the form of the machine shown in the drawings, the circular track 5 extends beyond 20 the hopper 6 so that after the carton is filled at the next movement of the carrier ring the filled carton will be pushed from beneath the hopper along on the track 5 and may then be removed in any manner desired.

25 In the machine shown in the drawings, which as previously stated, is of the type shown in Patents No. 714,875 and No. 716,007, the carton moving ring 1 is controlled by the tipping of the scale. The tipping of the scale beam under weight of the 30 filled package actuates the mechanism which shuts off the feed and also causes the carrier ring 1 to start. When the scale tips, a reciprocating member is caused to move in a direction to close the valve to the hopper 6 which is above the scales. The reciprocating frame mentioned comprises the two side rods 41 which slide in bearings 49 fixed to the side of the cylinder 44 and are connected at 35 their ends by the two cross-heads 42, 43. In one end of a double chambered cylinder 44 is a piston whose stem 45 is connected with the forward cross-head 42, and in the other end of the cylinder is a piston whose stem 46 is connected with the rear cross-head 43. Between the two pistons is an air chest 47 connected with a compressed air chamber and having ducts, not shown, which lead into the two chambers of the cylinder 44, one chamber 45 being in one end of the cylinder and the other chamber being in the other end, the two chambers being separated by the air chest 47 and open at their outer ends. Moving in the air chest 47 is a piston valve 48 which, as it rises and falls, admits air pressure alternately to the opposite chambers of the cylinder 44, and thereby drives the pistons 45 and 46 and moves the reciprocating frame to open and close the hopper valve.

50 The carrier ring 1 is intermittently driven by shaft 50 through intermediate gear and clutch mechanism, not fully shown, being in part covered by the box 51, the forward movement of the reciprocating frame which 55 closes the hopper valve causing the clutch

mechanism to be brought into engagement so as to operatively connect the carrier ring 1 with the driving shaft 50 and the movement of the reciprocating frame in the reverse direction to open the hopper valve causing the 70 disengagement of the clutch and thereby cause the carrier ring to stop.

Mechanism is connected with the scale beam and with the piston valve 48 which moves in the air chest 47, whereby the tipping of the scale actuates the valve 48 in such a direction as to admit pressure to one chamber of the cylinder 44 which drives the reciprocating frame in a direction to close the hopper valve, the movement of the reciprocating 80 frame engaging the clutch mechanism, as previously described, to give movement to the carrier ring, and the movement of the carrier ring actuates mechanism which, near the end of the movement of the carrier ring, 85 moves the piston 48 in the reverse direction and admits pressure to another one of the chambers of the cylinder 44 and opens the scale hopper valve.

The marking attachment is located so that 90 it will mark the carton either before or after it has reached the place of filling beneath the hopper according to whichever is desired. In the form of construction shown, it is located between the table 3, where the empty 95 carton has started, and the hopper 6.

The marking attachment and connections are as follows: Secured to, or forming a part of, the frame 7, which supports the carrier ring 1, is a bracket 8 which extends underneath the track 5 and radially outside of it, and has an upturned end 8' on which is mounted an arc shaped arm 9 whose inner face 9' is formed as an ink pad. Mounted on a shaft 10, which has its bearings in a boss 11 100 on the bracket 8, is a bell crank rocking lever having one arm 12 which extends into the path of the moving carton and another arm 12' which carries the marking disk 13. The bell crank lever is fast to the shaft 10, so as 105 to turn with it, being made fast either by driving fit or in any other suitable way. The bell crank lever is formed with a boss 14 whose lower end turns on the upper end of the boss 11 when the shaft turns on its axis. 110

Pivoted to the upper side of the arm 12' of the rocking lever near its outer end by a stud 15 is the marking disk 13. The marking disk may be either fast to the stud 15 and the stud 15 turn in bearings in the arm 12', or the 115 stud 15 may be fast to the arm 12' and the marking disk 13 turn on the stud. The stud 15 is provided with a head 16 which keeps the marking disk 13 from falling off. Preferably the marking disk turns on the 120 stud 15 which is screw threaded at its lower end and screwed into a hole tapped out in the arm 12'. When the carton 4 continues its movement from the position shown in Fig. 3 where it engages the arm 12 of the rocking 125

130

lever, it turns the rocking lever on its pivot, causing the periphery of the marking disk to roll on the inner curved face of the ink pad 9' until it moves past the end of the ink pad, 5 and as the rocking lever is still further turned, the marking disk will engage the outer face of the carton 4 as shown in Fig. 4 before the carton has passed out of reach. The engagement of the carton with the 10 marking disk as the carton moves along, will cause the marking disk to rotate and mark the carton with whatever date or other indicating mark it is provided with.

In order to return the rocking lever to its 15 normal position again after the carton has ridden past the end of the arm 12 of the rocking lever, a spring 17 is provided which is coiled around the shaft 10, one end of which is secured to the boss 11 on the arm 8 20 as by having an up-turned end 17' of the spring enter a slot in the boss, the other end of the spring being made fast to the shaft 10 or to a head 18 pinned to the shaft 10 as by a pin 19 or it may be fastened in any other suitable way.

In order to make sure that the marking disk 13, when returned to its initial position, is turned on its axis into just the position so that when it moves forward again the marking or dating stamp will always be in the right position to engage the carton when it moves forward instead of having the back side of the disk engage it, the disk is provided on its upper face with two oppositely disposed pins 20 which respectively engage stops 21 at the end of the return movement so that if in any way the disk has during the movement become rotated out of position, whichever one of the pins 20 strikes its stop 40 pin 21 first will cause the disk to turn on its axis until the other pin 20 strikes its stop 21 to bring it into the right position. These stop pins 21 are shown as projecting from a block 22 screwed to the end of the holder in 45 the ink pad 9.

In the modification shown in Fig. 6, the arm 12 of the rocking lever is shown as engaged by an arm 36 projecting directly from the carton moving finger 2. The arm 12 is 50 shown as somewhat longer than in Fig. 1 and as extending at a slightly different angle from arm 12', so that the rocking lever will be turned at the proper moment for the marking disk to engage the carton. It is obvious that the location and form of rocking lever and of the projection from the package moving ring which engages said rocking lever may be varied.

While I have shown and described the 60 rocking lever 12 as being engaged and actuated by the carton 4, it is obvious that instead of being actuated by the carton itself, it might be actuated by means of a finger projecting from the carrier ring 1 just in advance of the carton so as to swing the rocking

lever around to bring the marking disk into engagement with the carton at the proper time.

What I claim is:

1. In a package filling machine, a package 70 carrier, a marking disk, a pivoted lever having one arm which carries said marking disk and which normally holds said disk out of the path of the moving packages, said lever having another arm which extends into the 75 path of the moving packages and which is engaged successively by the moving packages to turn said lever on its fulcrum and thereby bring the marking disk into engagement with one of the packages.

2. In a package filling machine, a package carrier, a rocking lever having one arm carrying a rotary marking disk, the other arm of the rocking lever extending into the path of the moving packages and engaged successively by the moving packages to turn the 85 rocking lever on its fulcrum, thereby bringing the marking disk into engagement with one of the packages being moved by the carrier.

3. In a package filling machine, a rotating 90 package carrier, a rocking lever having one arm carrying a rotary marking disk, the other arm of the rocking lever extending into the path of the moving packages and engaged successively by the moving packages to turn 95 the rocking lever on its fulcrum, thereby bringing the marking disk into engagement with one of the packages being moved by the carrier, and means for turning the rocking lever back to its initial position after it 100 is released from engagement with said package.

4. In a package filling machine, a package carrier, a rocking lever having one arm carrying a rotary marking disk, the other arm of the rocking lever extending into the path of the moving packages and engaged successively by the moving packages to turn the 105 rocking lever on its fulcrum, thereby bringing the marking disk into engagement with one of the packages being moved by the carrier, and a segmental inking surface which is engaged by the marking disk during the movement of the rocking lever on its fulcrum.

5. In a package filling machine, a package 115 carrier, a rocking lever having one arm carrying a rotary marking disk, the other arm of the rocking lever extending into the path of the moving packages and engaged successively by the moving packages to turn the 120 rocking lever on its fulcrum, thereby bringing the marking disk into engagement with one of the packages being moved by the carrier, means for turning the rocking lever back to its initial position after it is released from engagement with said package, and means for centering the marking disk after each marking operation.

6. In a package filling machine, a rotating 130 package carrier, a rocking lever having one

arm carrying a rotary marking disk, the other arm of the rocking lever extending into the path of the moving packages and engaged successively by the moving packages to turn the rocking lever on its fulcrum, thereby bringing the marking disk into engagement with one of the packages being moved by the carrier, means for turning the rocking lever back to its initial position after it is released 10 from engagement with said package, and

guides which engage projections on the marking disk to center the marking disk after each marking operation.

In testimony whereof I affix my signature, in presence of two witnesses.

WILLIAM H. DOBLE.
